Patented Oct. 6, 1914.

2 SHEETS—SHEET 2.

UNITED STATES PATENT OFFICE.

ALBERT L. BROWN, OF LITTLE ROCK, ARKANSAS.

SAFETY APPLIANCE FOR AMMONIA-COMPRESSORS.

1,112,672.

Specification of Letters Patent.

Patented Oct. 6, 1914.

Application filed January 30, 1914. Serial No. 815,379.

To all whom it may concern:

Be it known that I, ALBERT L. BROWN, a citizen of the United States, and a resident of Little Rock, in the county of Pulaski and State of Arkansas, have invented certain new and useful Improvements in Safety Appliances for Ammonia-Compressors, of which the following is a full, clear, and exact specification.

This invention relates to ammonia compressors used in connection with the manufacture of ice, and has for its object to provide a safety appliance for automatically stopping the compressor and cutting off the supply of liquid ammonia to the ice tanks when the pressure in the pump cylinder becomes dangerously high.

A further object is to provide for automatically stopping the compressor whenever the engine starts to run away.

Still another object is to allow for operating said last mentioned safety device, for stopping the compressor when the engine starts to run away either by the use of the high pressure gas from the pump or by the use of steam from the source of supply from which the engine is run.

The invention will be first hereinafter described in connection with the accompanying drawings, which constitute a part of this specification, and then more specifically defined in the claims at the end of the description.

In the accompanying drawings, wherein similar reference characters are used throughout the several views to designate corresponding parts: Figure 1 is a diagrammatic view of a compressor with my safety appliance attached; Fig. 2 is an enlarged view partly in section of the members of the safety appliance which are arranged adjacent the compressor and governor, and Fig. 3 is a detailed sectional view of the liquid ammonia supply valve and its operating means.

In the drawings A designates an ice tank to which the liquid ammonia is fed by a pipe B from the receiver C, and from which tank the ammonia gas is pumped by the compressor pump D via pipe E and forced to the condenser F via pipe G. The condensed ammonia is conveyed from the condenser back to the receiver C by a pipe H from whence it may be again distributed to the ice tanks.

Steam for running the engine is supplied

to the steam chest K by a pipe L. The steam chest is fitted with "knock off blocks" or valves M, the turning of which in the manner to be hereinafter described will cut off the supply of steam to the engine and consequently cause it to stop.

The engine governor N comprises the usual pair of weighted arms 4 operatively attached to a vertically movable upright 5 pivotally attached at 6 near its lower end to one end of a lever 7 which is intermediate pivoted at 8. The other end of said lever carries a counter balancing weight 9 and is connected to the stem 10 of a piston valve 11 mounted in a casing 12. Secured to the lever 7 so as to turn therewith, is a transverse member 13 constituting upwardly and downwardly extending lever arms. The ends of these lever arms are connected to the "knock off blocks" or valves M by rods 14.

A branch pipe 15 from the pipe G leads to a safety valve 16 which, when the pressure of gas in the pump cylinder D becomes dangerously high, will open and permit said gas to enter a pipe 17 which leads to the casing 12 and opens into the same below the piston valve 11. The pipe 17 has a branch 18 leading to the casing 19 of a valve 20 for controlling the distribution of the liquid ammonia from the receiver C to the ice tanks. The stem 21 of the valve 20 carries a disk 22 fitted to slide in the casing 19. The valve 20 is normally held open to permit the flow of the liquid ammonia from the receiver C to the ice tanks by a spring 23. When, however, the high pressure gas from the compressor enters the casing 19 via pipe 18, it operates against the disk 22 to close the valve against the tension of the spring 23, thereby automatically cutting off the supply of liquid ammonia to the ice tanks.

The piston valve 11 is normally held down in the position illustrated by a spring 24, but when the high pressure gas is supplied by the pipe 17 to the casing 12 below said valve the latter is moved upward against the influence of the spring with the result that the lever 7 is turned sufficiently to operate the "knock off blocks" or valves M, through the instrumentality of the lever arms 13 and connecting rods 14, for cutting off the steam supply to the engine and stopping the same. The upright 5 of the governor rests upon a spring 25. When

the engine is running slowly, this spring 25 will take the weight of the governor and prevent it from turning the lever 7 and arms 13 and shutting down the engine.

5 When the piston valve 11 is raised by pressure of gas in the casing 12, the spring 25 yields to permit the lever 7 to turn and shut down the engine.

It will thus be seen that when the pressure of the pump cylinder D becomes dangerously high, as may result from omitting to open the supply valve 28 in the pipe C or other cause, the high pressure gas will open the safety valve 16 and pass to the 15 valve cylinders 12 and 19 via the pipes 17 and 18, respectively, and operate the valves 11 and 20 to automatically shut down the engine and cut off the supply of liquid ammonia to the ice-tanks.

20 To provide for stopping the engine automatically when it starts to run away, I have provided another piston valve 27 arranged in a cylindrical casing 28. A branch pipe 29 leads from the pipe 15, back of the safety valve 16, to the upper portion of this casing 28 so that said branch pipe 29 will always be filled with gas from the pump cylinder D. Another pipe 30 leads from the lower portion of the casing 28 to the casing 12 of the piston valve 11, opening below said valve. Normally the valve 27 is positioned so as to cut off the gas supplied by the pipe 29 from entering the pipe 30. The stem 31 of the valve 27 extends up wardly 35 and carries two adjustable collars 32 and 33 secured by set screws 34 and 35, respectively. A loose collar 36 is arranged on said valve stem between the adjustable collars, and below said loose collar there 40 extends a rigid arm 37 from the upright 5 of the governor. A spring 38 interposed between said arm 37 and the lower adjustable collar 32 normally holds the valve 27 in the position illustrated. Now, when the 45 engine starts to run away, the upright 5 is moved upward, first bringing the loose collar 36 into contact with the upper adjustable collar 33 and then raising the valve stem 31 and moving the valve 27 upward 50 above the inlet port of the pipe 30. As soon as this occurs, the gas from said pipe 29 will pass into the casing 12 of the valve 11 via pipe 30 and raise said valve, thereby permitting the lever 7 to turn and shut 55 off the supply of steam to the engine through the instrumentality of the lever arms 13, connecting rods 14 and "knock off blocks" or valve M, as already described. By adjusting the collars 32 and 33 on the valve 60 stem 31, the governor may be made to automatically shut down the engine at any desired speed. This automatic operation of the valve 11 for shutting down the engine when the engine starts to run away may be 65 accomplished by steam furnished to the up-

per portion of the casing 28 by a branch pipe 39 from the steam supply pipe L. The steam may be used to supplement the gas, or either steam or gas may be used alone, as desired. When the engine is to be started up again, it is only necessary to relieve the pressure in the casing 12 of the valve 11, as by cock 40, Fig. 2, whereupon all the parts of my safety appliance will return to normal position, as illustrated.

Having thus described my invention, what I claim as new and desire to secure by Letters Patent of the United States is:

1. The combination with a compressor, of a piston valve, means for shutting down the engine operatively connected to the piston valve, a governor, a second piston valve controlled by the governor, and pipes leading from the pump cylinder and the first piston valve casing to the casing of the second piston valve, said latter valve normally cutting off flow from one pipe to the other in the casing thereof, but adapted to be moved so as to establish communication between said pipes when the governor reaches a predetermined speed.

2. The combination with a compressor, of a piston valve, means for shutting down the engine operatively connected to said piston valve, a governor, a second piston valve controlled by the governor, adjustable means of connection between the second piston valve and the governor, whereby the valve may be set to be operated at various speeds of the governor, and pipes leading from the pump cylinder and the first piston valve casing to the casing of the second piston valve, said latter valve normally cutting off flow from one pipe to the other in the casing thereof, but adapted to be moved so as to establish communication between said pipes when the governor reaches the predetermined speed.

3. The combination with a compressor, of a piston valve, means for shutting down the engine operatively connected to said piston valve, a governor, a second piston valve, an adjustable collar on the stem of said second piston valve, a loose collar also mounted on said valve stem, an arm rigidly connected to the governor and extending below the loose collar, whereby the second valve is adjustably controlled by the governor, and pipes leading from the pump cylinder and the first piston valve casing to the casing of the second piston valve, said latter valve normally cutting off flow from one pipe to the other in the casing thereof, but adapted to be moved so as to establish communication between said pipes when the governor reaches the predetermined speed.

4. The combination with a compressor, of a piston valve, means for shutting down the engine operatively connected to said piston valve, a governor, a second piston valve, two adjustable collars on the stem of said sec-

ond valve, a loose collar also mounted on said valve stem and arranged between the two adjustable collars, an arm rigidly connected to the governor and extending below 5 the loose collar, and a spring interposed between the lower adjustable collar and the arm from the governor, whereby the second valve is adjustably controlled by the governor, and pipes leading from the pump cylinder 10 and the first piston valve casing to the casing of the second piston valve, said latter valve normally cutting off flow from one pipe to the other in the casing thereof, but adapted to be moved so as to establish communication 15 between said pipes when the governor reaches a predetermined speed.

5. The combination with a compressor, of a piston valve, means for shutting down the engine operatively connected to the piston 20 valve, a governor, a second piston valve controlled by the governor, and pipes leading from the source of supply of steam for running the engine and from the first piston valve casing to the casing of the second piston 25 valve, said latter valve normally cutting off flow from one pipe to the other in the casing thereof, but adapted to be moved so as to establish communication between said pipes when the governor reaches a predetermined speed.

6. The combination with a compressor, of a piston valve, means for shutting down the engine operatively connected to the piston 30 valve, a governor, a second piston valve controlled by the governor, and pipes leading

from the pump cylinder of the compressor, from the source of supply of steam for running the engine and from the first piston valve casing to the casing of the second piston valve, said latter valve normally cutting off flow from either of the pipes leading from the steam supply source or from the pump cylinder to the pipe leading from the casing of the first piston valve, but adapted to be moved so as to establish communication 40 between said pipes when the governor reaches a predetermined speed.

7. The combination with a compressor, of a piston valve, a pipe leading from the pump cylinder of said compressor to the casing of the piston valve, a safety valve in said pipe, a lever operatively connected to said piston valve, means operatively connected with said lever for shutting down the engine when said lever is moved by the piston valve, a 50 governor connected to said lever, a spring for yieldingly supporting the governor as and for the purpose specified, and a second valve controlled by the governor, and means connected to said second valve for supplying an actuating fluid to the first valve when the engine starts to run away.

In testimony whereof I have signed my name to this specification in the presence of two attesting witnesses.

ALBERT L. BROWN.
